BURCHARD THOENS, OF NEW YORK, N. Y.

FLUSHING-VALVE.

1,265,832.

Specification of Letters Patent.

Patented May 14, 1918.

Application filed July 7, 1915. Serial No. 38,594.

To all whom it may concern:

Be it known that I, BURCHARD THOENS, a subject of the Emperor of Germany, residing in the city, county, and State of New York, have invented certain new and useful Improvements in Flushing-Valves, of which the following is a specification.

My invention relates to flushing apparatus used in connection with toilets and has particular reference to a valve which may be directly connected with the main water pipe in the building. This avoids the necessity of interposing a tank, siphon or similar device, the valve being designed so that it will automatically stop the flow after a predetermined quantity of water has passed through it.

The principal object of my invention is to provide a device of this character which will not leak and in which the parts are simple and few in number.

The main features of the invention comprise the mechanism for releasing the valve after it has been opened, and cushioning the seating of the valve.

The above and other objects and the novel features of the invention will be set forth in the following description, accompanied by the drawing, in which,

30 Figure 1 is a vertical sectional view of the valve as it appears when opened; and

Fig. 2 is a detail view showing the position of the valve and the direction in which water flows when the valve is closed.

35 The casing for the valve comprises a bottom member 10 and a top or cap member 11 which are secured together at the flanges 101 and 111 respectively. The cap member 11 has a threaded nipple 12 to which the water pipe of the building is connected and which is provided with an inlet opening 13. The bottom part 10 of the casing has a depending threaded nipple 14 open at 15 and adapted to be connected to the flush pipe of

45 the toilet.

The outlet of the casing at 16 has a conical valve seat 17 surrounding it to fit the conical part 18 of a valve 19. The valve 19 has ribs 20 and a stem 21 on its under side, the ribs guiding the valve vertically. The valve may be raised off its seat by any suitable device and in the construction shown an arm 22 engages the end of the stem 21. The arm 22 is fixed on a rock shaft 23 pivotally supported in a cavity 24 in the side of the depending part 14 of the casing.

The outside end of the shaft 23 has an arm 25 connected thereto and a chain 26 depends from the outer end of the arm 25.

The valve 19 has a stem 27 extending upwardly therefrom, the inlet 13, outlet 16 and valve 19 being coaxial. The upper end of the valve stem 27 has a head on sleeve 28 secured thereto which is guided in a cylinder 29. The cylinder 29 is supported on the shoulder 30 by a member 31 and has an opening 32 in one side thereof.

The bottom of the opening 32 is of sufficient height above the bottom of the cylinder 29 to provide a hydraulic cushion for the valve, to prevent the valve from striking its seat suddenly and pounding it, which would cause it to leak after a short time. The head 28 operating in the cylinder 29 acts as a dash pot for the valve. The lever 33 pivoted at 34 has one arm 35 which engages beneath the shoulder 36 formed by the head 28 and holds the valve off its seat when the said valve has been raised by the operating device. While the valve is open water flows directly from the inlet 13 through the outlet 16 to the flush pipe and means are provided to release the valve after a predetermined quantity of water has flowed through the valve.

Means for releasing the lever 33 comprises a piston 37 which has a yoke 38 on its upper side fitting over the end 39 of the lever 33. The piston 37 moves substantially parallel to the valve 19 and works in a cylinder 40 in the casing at one side of the valve. The cylinder 40 is formed by one wall of the casing 10 and by a wall 41 curved to correspond to the wall of the casing 10. A spring 42 is secured to the lever 33 and extends into engagement with the wall 41 and stop 44 and normally tends to hold the end 35 of the lever projecting through the opening 32 and in engagement with the valve stem or the head 28 thereon so that when the valve is lifted off its seat the end 35 will engage under the head 28.

The cylinder 40 is open at its upper end nearest the inlet 13 and the main water pressure will therefore be exerted against the upper end of the piston. The piston is supported at the limit of its upward travel and against the stop 44 by the spiral spring 45 which rests in the bottom of the cylinder 40. The cylinder 40 is also permanently open at its bottom end and by means of the passages 46 and 47 communicates with the interior of the casing 10, so that normally the main wa-

ter pressure will be exerted also against the bottom side of the piston 37 and the latter will be supported from the bottom side, the pressure of the spring 45 and water serving 5 to sustain it in its normal position, but the spring 45 being insufficient for that purpose when the water pressure is removed from the bottom side of the piston. The effective size of the duct formed by the passageways 10 46 and 47 may be altered by the screw 48, which will also determine the time it takes for the water to flow through the valve before it is closed.

The passageway 47 has its outlet located 15 at a point adjacent the seat 17 of the valve 19 so that when the valve is lifted off its seat it will be raised above the outlet end 50 of the passageway 47 and water will flow out of the cylinder 40 at the same time that water 20 flows from the casing 10 through the outlet 16, as indicated by the arrows in Fig. 1. The discharge of the water from the cylinder 40 removes the water pressure from the bottom side of the piston 37 and as soon as 25 the latter has lowered a sufficient amount due to the water pressure against the upper side thereof, the yoke 38 on said piston will engage the end 39 of the lever 33 and withdraw the end 35 from beneath the shoulder 36, allowing the valve to drop to its seat. The drop will not be sudden but will be cushioned by the dash-pot action of the water in the cylinder 29, as heretofore explained. The main water pressure against 30 35 the top side of the valve will act on the valve and force it to its seat and consequently there will be no wire drawing and therefore no leakage. The conical valve which tightly fits in the conical valve seat also prevents 40 leakage.

As the valve returns to its seat it passes across and sufficiently below the end 50 of the passageway 47 to permit water from the main water supply to enter that passageway, 45 as indicated by the arrow in Fig. 2, and to flow into the cylinder 40 which will cause the piston 37 to rise in the cylinder and assume its normal position.

By my arrangement the operating or actuating means which is accessible outside of 50 the valve does not enter the high pressure chamber and thus stuffing boxes and similar devices are unnecessary and prevent leakage. The conical valve and valve seat may be 55 ground to a perfect fit so as to keep them from leaking. The release piston 37 is balanced by water pressure on both sides when the valve is closed and when the valve is opened a release of the pressure on one side 60 serves to operate the piston, the vacuum caused by the flow of the water through the outlet reducing the pressure below the release valve.

While I have shown and described the 65 device in detail, I do not wish to be limited

to the exact form shown as it is clear that minor changes may be made therein without departing from the spirit of the invention.

Having described the invention what is claimed and desired to be secured by Letters 70 Patent is:—

1. In a flushing valve, the combination of a casing having an inlet and an outlet, a valve in said casing controlling said outlet, means for operating said valve, a device for holding said valve open, and means for releasing said device after a predetermined time so that said valve may close said outlet, said releasing means comprising a piston and a cylinder in which said piston works, said cylinder having a passageway connected therewith which constitutes an inlet and outlet for said cylinder, the outer end of said passageway being located near said valve controlled outlet, the valve operating so that 80 it will be on one side of the end of said passageway when the valve is open and on the opposite side when the valve is closed, whereby water may flow from said cylinder across one side of said valve when said valve is 85 open and into said cylinder across the other side of said valve when the valve is closed.

2. In a flushing valve, the combination of a casing having an inlet at the top and an outlet at the bottom thereof, a valve in said 95 casing controlling said outlet, means for operating said valve, a device adapted to engage said valve and hold it open when it has been operated, means for operating said device to release said valve after a predetermined amount of water has flowed through 100 said outlet, said releasing means comprising a cylinder open at one end to the water pressure and having a passageway in communication with its other end which constitutes 105 an inlet and an outlet and opens at a point adjacent the outlet of the casing, a piston in said cylinder and normally sustained in a predetermined position, the water pressure at one side of said piston being removed 110 when said valve is open and the water flowing out of said cylinder through said passageway and out of the casing through said outlet therein, whereby said piston operates said device to release the valve, to permit 115 said valve to close said outlet in the casing, permitting water to flow into said cylinder through said passageway to return said piston to its normal position.

3. In a flushing valve, the combination of 120 a casing having an inlet at the top and an outlet at the bottom, a conical valve seat at said outlet, a conical valve controlling said outlet and seating on said valve seat, means for operating said valve, a device adapted to hold said valve open when the same has been operated by said means, means for operating said device to release said valve after a predetermined amount of water has 125 flowed through said outlet, said releasing 130

means comprising a cylinder open at one end to the main water pressure and having a passageway leading from its other end to a point adjacent the said valve seat, said 5 passageway constituting an inlet and an outlet for said other end of the cylinder, a piston working in said cylinder and normally sustained in a predetermined position and normally having the main water pressure 10 on opposite sides thereof, said valve being adapted to be raised above the outlet end of said passageway, whereby the water pressure at one side of said piston is removed and said piston descends in the 15 cylinder and operates said device to release the valve, said valve when released returning to its seat and moving across the end of said passageway and water entering said passageway and cylinder to restore said 20 piston to its normal position.

4. In a flushing valve, the combination of a casing having an inlet at one end and an outlet at the other end, a valve in said casing controlling said outlet and having a 25 stem extending into the casing, a head on said stem, and a sleeve fitting said head and coöperating therewith to form a dash pot to cushion said valve, means for operating said valve, a pivoted lever adapted to engage the head on said valve stem and hold 30 said valve open when it has been operated, and means for operating said device to release said valve after a predetermined amount of water has flowed through said 35 outlet, said releasing means comprising a cylinder in said casing and open adjacent the inlet end of said casing, said cylinder having a passageway at its other end leading to a point adjacent said outlet of the 40 casing, said passageway constituting both an inlet and an outlet for said other end of the cylinder, a piston working in said cylinder and having water pressure on its opposite sides, and a spring in the cylinder 45 supporting said piston, the water at the lower side of said piston flowing out through said passageway and out of the casing through said outlet when said valve is open, whereby the piston moves in said 50 cylinder and engages said lever to release the valve after a predetermined movement of the piston, said passageway serving to admit water into said cylinder when said valve is closed, whereby the piston is re- 55 stored to its normal position.

5. In a flushing valve, the combination of a casing having a chamber provided with

an inlet and an outlet below said inlet, a valve seat adjacent said outlet, a valve controlling said outlet and fitting said seat, 60 means for operating said valve, means for holding said valve open a predetermined interval of time comprising a cylinder, a piston working in said cylinder, said cylinder having one end thereof open to water 65 pressure from said inlet and having a duct connected to the other end thereof, said duct leading to a point adjacent said valve seat, whereby when said valve is seated water may flow over one side of said valve 70 into said cylinder to balance the pressure on opposite sides of said piston, and whereby when said valve is open water may flow from said chamber and from said cylinder into said outlet under said valve to release 75 the pressure on one side of said piston.

6. In a flushing valve, the combination of a casing having an inlet at one end and an outlet at the other end in line with said inlet, a valve seat adjacent said outlet, a 80 valve in said casing controlling said outlet and fitting said seat, said valve having a stem, the axis of which is located in the center line between said inlet and outlet, means for operating said valve, and means 85 for holding said valve open a predetermined interval of time comprising a cylinder having one end thereof open to water pressure from said inlet, a piston working in said cylinder, the other end of said cylinder being 90 adapted to receive water to balance the piston in the cylinder when said valve is closed and being adapted to discharge water to release the pressure on one side of the piston 95 when said valve is open.

7. In a flushing valve, the combination of a casing having an inlet and an outlet, a valve in said casing controlling said outlet, said valve having a stem extending into the casing, means for operating said valve, hydraulic means for cushioning said valve as it closes the outlet, said hydraulic cushioning means comprising a water chamber in the casing and a head carried by said valve stem and working in said water chamber, 100 a trip engaging the head on said valve stem and holding said valve open when the same is operated, and means for releasing said valve after a predetermined interval of time comprising a fluid operated device for 105 disengaging said trip from said head on the valve stem.

In testimony whereof I affix my signature.
BURCHARD THOENS.
